UNITED STATES PATENT OFFICE

126,449

DESIGN FOR A COMBINED MIRROR AND COMPACT

David W. Dunberg, New York, N. Y.

Application March 13, 1941, Serial No. 99,544

Term of patent 7 years

To all whom it may concern:

Be it known that I, David W. Dunberg, a citizen of the United States of America, residing in New York city, county of New York, and State of New York, have invented a new, original, and ornamental Design for a Combined Mirror and Compact, of which the following is a specification, reference being had to the accompanying drawing, forming part thereof.

Fig. 1 is a front perspective view of a combined mirror and compact showing my new design.

Fig. 2 is a front perspective view illustrating the compact in open position with the mirror extended.

Fig. 3 is a rear elevational view of Fig. 2.

I claim:

The ornamental design for a combined mirror and compact, as shown and described.

DAVID W. DUNBERG.
